CONVERTIBLE FURNITURE

Frederick D. Schneider, Hillside, N. J., assignor to
Else Geuder Schneider, Hillside, N. J.

Application June 30, 1932, Serial No. 620,098

20 Claims. (Cl. 155—130)

My invention pertains to convertible furniture and more particularly to a plurality of separate pieces of furniture designed so as to be adapted for assembly so as collectively to 5 construct a single piece of furniture.

The drawings exemplify embodiment of the principles of my invention in four chairs and a table which when separated will exercise their ordinary function as pieces of furniture, but 10 which may be compactly assembled and inter-fitted so as to require no special securing or interlocking means whereby to constitute a lounging chair, duplex settee, laterally enclosed couch or conversation chair.

15 Folding chairs and table have become progressively more popular, not only for card playing, because of their economy, mobility, and ease of removal when folded for storage. However, such furniture pieces have commonly been used

20 for only a small per cent of time and, except occasionally for the serving of informal luncheons, have not been regarded as sufficiently stable, comfortable or ornamental for continuous appearance in the home or hotel. When

25 not in use they have required storage space which might otherwise usefully or needfully be available, especially in some modern apartments where no excess space is to be found. Ac-cordingly, the object of my invention is to make

30 the separate pieces of furniture convertible to alternative use with simplicity and facility of the converting operation and without involving discouraging manufacturing expense. While I have exemplified one form of my invention as

35 a conversion of a table and four chairs into a lounging chair or the reverse, I have not supposed it necessary to limit my claim to such specified articles of furniture, but instead, in-tend to cover the convertible principle which

40 is not dependent upon hinges, links or other connecting or attaching devices. My familiarity with some of the prior marketed art war-rants such a supposition. Nor am I dissuaded by my knowledge of the disclosure of prior pat-

45 ents including Horneburg No. 567,595 of Sep-tember 15, 1896; Huether No. 654,639 of July 31, 1900; Gauvin, Jr. and Moore No. 789,364 of May 9, 1905; Switzer No. 1,017,342 of February 13, 1912; Perry No. 1,258,141 of March 5, 1918;

50 Austin No. 1,271,830 of July 9, 1918; Eck-en-walder No. 1,484,630 of February 26, 1924; Giard No. 1,520,641 of December 23, 1924; Scharl No. 1,535,044 of April 21, 1925; Scholnhammer No. 1,773,501 of August 19, 1930.

55 The drawings further exemplify three modi-

fied forms or structural arrangements embody-ing principles of my invention, in two forms there being used with four chairs, a table to interlock them while in its inverted position and according to another form using duplicate 60 chairs with a table having hinged along one edge an element adapted alternatively to lie against the underside of the table top or to be swung upwardly when the table is in its in-verted position so as to constitute a rest for 65 a lounging chair of which the backs of the duplicate chairs shall constitute lateral arm rests; the other using two pairs of duplicate chairs and one pair of which comprises in ad-dition to back rests lateral arm rests, which 70 four chairs (duplicated in pairs) are then ar-ranged in closely nested position with duplicate-chairs in diagonally opposite corners.

Adverting to the drawings:

Figure 1 is a perspective view of a separated 75 card table and four chairs embodying the features of my invention. Figure 2 is a per-spective view of the same five units shown in Figure 1 converted into a lounging chair. Fig-80 ure 3 is an enlarged front elevation of Figure 2 with a table flange sectioned and showing in dotted lines the legs of the table projecting up into the backs of the chairs. Figure 4 is a horizontal section on line 4—4 of Figure 3. Figure 5 is a perspective view of one of two 85 duplicate chairs. Figure 6 is a perspective view of one of a pair of right and left hand chairs. Figure 7 is a vertical section through a modified form of table in its inverted pos-90 ition and having hinged thereto a back rest forming element also shown in dotted lines in its alternative position whereby when such a 95 table is employed four duplicate chairs like the one shown in Figure 5 might be employed. Fig-ure 8 is a broken view showing how the table modification of Figure 7 cooperates with dupli-cate chairs. Figure 9 is a perspective view of a 100 second modification wherein two pairs of dupli-cate chairs, one pair differing from the other, may be rearranged on an inverted table hav-ing folding legs entering slots in the edges of the chairs. Figure 10 is a horizontal section of Figure 9 taken on a line above the seats. Figure 11 is a perspective view of an altered 105 arrangement for nesting four duplicate chairs as a duplex settee.

In Figure 1 there may be observed two dupli-cate chairs 1, having rather low back rests 2 and seat portions 3. The design of the chairs 1 will of course vary depending upon whether made 110

of wood or steel, but it is merely of consequence to this invention that the back rests proper do not extend as high as usual above the seats and that the sides, fronts and backs of the chairs 5 may be brought into close abutting relationship. The backs of the chairs 1 are provided in each corner with a bore or hole 4 which is open below and extends upwardly to terminate short of emergence through the top.

10 A pair of what I term right hand and left hand chairs shown in Figure 1 will preferably have the same height and size of seat and the same height of back rest. In Figure 6 the right hand chair 5 includes a back rest 6, a seat 7 and a right side arm rest 8 which is of the same height as the back rest 6. Upholstering or cushioning of the chairs will be optional. The chair 5 is similarly provided at the junction of its back 6 and arm rest 8 with an upwardly extending hole 9 which is open at its base. The left hand chair 10 shown in Figure 1 comprises a back rest 12 and seat 11 which are of the same size and shape as the back rests 2 and seats 3 and back rest 6 and seat 7 respectively. The chair 25 10 is provided with an arm rest 13 precisely like the arm rest 8 on the chair 5 except that it is along the left side instead of along the right side. The corner of the chair 10 is provided with an upwardly extending hole 14 which corresponds to the hole 9 in its companion chair.

A table comprises a top 15 of a predetermined shape and size for reasons which will hereinafter appear. At its four corners the table top carries four upwardly projecting cup-shaped members 35 16 adapted when so positioned to serve as glass holders or ash trays. The margin of the top is defined by a quadrilateral depending flange 17 which encloses the upper ends of four corner table legs 18 designed to fit, one pair in two of the holes 4 and the other pair in the holes 9 and 14 when the table is inverted as shown in Figures 3 and 4. In such inverted position of the table the cup-shaped members 16 will function as very short legs for the converted piece of furniture comprising the assembled units to constitute as appears in Figure 2 a lounging chair preferably to contain one or more cushions not shown.

The size of the table top which is enclosed by the upwardly projecting flange 17 when the table 50 is inverted, is such that it very slightly exceeds the combined areas of the bases of the two chairs 1 and of the chairs 5 and 10 to permit the flange 17 snugly to confine the bottoms of all four chairs when arranged as shown in Figures 55 2 and 4. In bringing the chairs of light weight to such an arrangement each is lifted high enough to permit insertion of one table leg 18 into its hole 4, 9 or 14. When assembled as shown in Figure 2 the flange 17 will prevent dis- 60 placement of the compact internested chair arrangement and the interlocked arrangement by reason of the occupancy by the legs 18 of four of the holes 4, 9 and 14 will prevent tipping of the chairs. The Figures 2 and 4 show the 65 seats and the interiors of the back and arm rests upholstered as designated by the single numeral 19 in Figure 4. As before stated such cushioning may selectively be omitted as fixed elements of the chairs.

70 I record my realization that the bottoms of the chair legs might occupy appropriately shaped recesses in the inverted table top in lieu of confinement by a table top flange and to serve the equivalent function of preventing chair displacement as well as proper initial arrangement.

The modification of Figures 7 and 8 involves a table 20 provided with a flange 21 and convertible back rest 22 hinged at 23 along the inside of one flange section. Four duplicate chairs 24 are then arranged front to front in pairs and side to side as other pairs after the convertible back rest 22 has been swung up to its dotted line position in Figure 7 in which it will serve as a back rest extending across one end of the composite lounging chair wherein the back rests of the four chairs 24 constitute arm rests.

The modification disclosed by Figures 9 and 10 pertains to a table 25 having two of its diagonally opposite legs 26 hinged. Two plain chairs 27 like the chair shown in Figure 5 are arranged with their backs 28 staggered near the middle line of the table. Two duplicate chairs 29 like the chair 10 shown in Figure 1 are arranged as shown to occupy the two opposite corners. The chairs 29, in addition to holes at table corners, have their seat supports fashioned with slots 31 (see Figure 9) to be occupied by the two hinged legs 26 when they are folded down against the top. Such an arrangement will constitute 100 what is known as a duplex or face-to-face "conversation" chair.

Figure 11 shows an arrangement for achieving a duplex settee, wherein a table 32 has all four of its legs 33 hingedly adapted to fold 105 flat against the underside of the table top which is enough larger in area to permit four duplicate chairs 34 of steel framing to be arranged in pairs back to back inside of the rectangle defined by the four folded table legs. Securing 110 bolt and wingnut combinations 35 are carried by the lower chair fronts and each adjacent pair is adapted when turned to clamp the legs of two correspondingly faced chairs after having entered through the slots 37 which are appropriately positioned in two oppositely disposed sections of the table flange 36.

It is to be realized that the scope of my invention comprehends many equivalent constructions. The showing of the drawings and the 120 particular description are merely specific exemplifications of a plurality of mechanical embodiments and arrangements.

I claim:—

1. Convertible furniture comprising a pair of 125 chairs one provided on one side and the other one on the opposite side with a wall extending from top to bottom and an inverted table for securing said chairs in appositioned relation with front edges of said walls, considering the chairs 130 as separated, abutting each other and serving as a composite back rest, whereby to construct a lounging chair with double seat area and with the back rests of said duplicate chairs, when separated, adapted to serve as lateral arm rests. 135

2. Convertible furniture comprising a pair of 140 chairs each including supporting sections, seat and back rest, each of said chairs additionally provided on one side with a permanent up- standing wall extending to the front edge of its 145 seat, a pair of duplicate chairs conforming in size and shape of seat and back rest to said first mentioned pair of chairs and an inverted table for securing said first mentioned pair of chairs in appositioned relation with front edges of said walls abutting each other and for securing said last mentioned pair of chairs alongside said first mentioned pair of chairs respectively and in apposition to each other, whereby to construct a lounging chair with quadruple seat area 150

and with the back rests of all of said chairs adapted to serve as arm rests.

3. Convertible furniture comprising five units, namely, a pair of duplicate chairs each including a seat-supporting section, seat and back rest, said chairs being furthermore provided on one side with a wall extending from front to back, a pair of duplicate chairs conforming in size and shape of seat and back rest to said 10 first mentioned pair of chairs and a table adapted in its inverted position to secure said first mentioned pair of chairs in appositional relation and with the front edges of said walls abutting each other and likewise adapted to 15 secure said last mentioned pair of chairs alongside of said first mentioned pair of chairs respectively and in apposition to each other, whereby to construct a lounging chair with quadruple seat area and with the back rests of 20 all of said chairs adapted to serve as arm rests, the legs of said table and raised sections of said chairs being interfitted.

4. Convertible furniture comprising a plurality of chairs arranged in abutting relation to form 25 a chair assembly and having openings open at their lower ends, and an inverted table for interlocking said chairs as a unit, the legs of said table occupying said chair openings respectively.

5. Convertible furniture comprising a plurality 30 of chairs having elongated openings extended into the backs thereof, said chairs being arranged in abutting relation to form a chair assembly and an inverted table having legs entered in said openings respectively, the top of said 35 table when in its normal position carrying receptacles at corners thereof, said receptacles when the table is in its inverted position serving as legs whereby to hold said chairs raised from the floor.

40 6. Convertible furniture comprising a plurality of low-backed chairs, a table having a top bordered by an encompassing flange which depends during the normal table-functionating position and which flange is adapted partially 45 to enclose the legs of said chairs when said table is in an inverted position, the back rests of some of said chairs being in edge abutment while supported upon the inverted table and means for securing the assembled units together.

50 7. Convertible furniture comprising four low-backed chairs, said chair backs being fashioned with holes, and a table having legs and a top bordered by an encompassing flange which depends during the normal table-functionating position and which flange is adapted to enclose in four corner arrangement the lowest leg portions of said chairs when said table is in an inverted position, said table legs occupying said holes respectively, two of said chairs having 55 angularly disposed back and arm rests conforming to two sides of said chairs and while supported upon the inverted table being in edge abutment with each other and with the two other chairs respectively whereby to constitute 60 the composite back and composite lateral arm rests of a lounging chair.

8. As convertible furniture, the combination 65 of right and left chairs each comprising a seat a backrest and one lateral armrest, a pair of 70 duplicate chairs each comprising a seat and thereabove only a backrest, certain portions of all four chairs being of the same size and shape, and a table bordered by a flange encompassing the combined floor-adjacent sides of said chairs 75 and confining the chairs as an assembled unit,

with pairs of like chairs appositioned with the front edges of their seats abutting each other and with said armrests of said first-mentioned pair of chairs along one border of the assembly whereby said armrests constitute a composite backrest for a constructed chair of quadruple seat size and whereby pairs of the four individual chair backs each constitute a lateral armrest for the converted chair assembly.

9. Convertible furniture comprising a plurality of substantially similar furniture pieces each having a plurality of edges adapted contactually to nest together a different kind of furniture piece when in its inverted position snugly enclosing portions of said plurality of substantially similar pieces while in nested assembly, and means for interlocking all the pieces when in such interfitted relation whereby collectively to construct a distinct piece of furniture.

10. Convertible furniture comprising a plurality of furniture pieces of like function having edges adapted contactually to nest together, a different kind of furniture piece bordered by a flange conforming to outer borders of said first mentioned pieces when nested, said flange snugly enclosing lower portions of said nested furniture pieces when the flange-carrying furniture piece is in its inverted position, other portions of one kind of furniture being confined by the other kind of furniture whereby to construct a distinct article of furniture having its constituent parts interlocked.

11. Convertible furniture comprising a plurality of chairs, and a table having depending portions in their inverted position snugly enclosing said chairs while the latter are resting upon segments of said table top, said table being provided with a hinged member adapted to be swung at an angle to said table top and to constitute an end rest extending between the back 115 rests of two of said chairs as a part of a compositely enlarged chair.

12. Convertible furniture comprising a plurality of duplicate chairs each having seat-defining edge portions adapted for bilateral interfitting 120 with edges of two adjacently arranged ones of said chairs and having only backrests above their seats, a table presenting upstanding portions in its inverted position in tongue and groove connection with said chairs respectively, and a member hinged to the table and alternatively adapted to lie against the table top or to constitute an end rest extending between the lateral edges of the spaced backrests of two of said chairs, and to constitute the backrest of a lounging 130 article of furniture having as armrests the backs of said chairs.

13. Convertible furniture comprising a plurality of chairs having only back rests above their seats, a table having its top fashioned with 135 a downwardly flanged margin snugly enclosing the bases of said chairs when the table is inverted, and a member hinged along one edge of said table and alternatively adapted to lie against the table top or to constitute an end rest extending between the lateral edges of the spaced back rests of two of said chairs and to constitute the back rest of a lounging article of furniture having as arm rests the backs of said chairs, said chair backs being provided each with an 140 aperture occupied by a leg of said inverted table whereby in cooperation with the table flange to secure the chairs against both tipping and base separation.

14. Convertible furniture comprising five units, 150

- namely, a pair of chairs each including a seat-supporting section, seat and back rest, said chairs being furthermore provided on one side with a section raised above said seat, a pair of 5 duplicate plain chairs conforming in size and shape of seat and back section to said first mentioned pair of chairs and a table in its inverted position securing said first mentioned pair of chairs in apposited relation with the front 10 edges of said raised side sections juxtaposed to each other and likewise securing said last mentioned pair of chairs alongside of said first mentioned pair of chairs respectively and in apposition to each other, whereby to construct a lounging chair with quadruple seat area and with the 15 back rests of all of said chairs adapted to serve as arm rests, the legs of said table and raised sections of said chairs being interfitted.
15. Convertible furniture comprising four 20 chairs arranged in abutting relation about a central point to form a chair assembly and means comprising an inverted table having a top supporting said chairs and having up-standing edge portions adapted to embrace said chairs.
16. Convertible furniture comprising a plurality of chairs arranged in endless abutting relation about a central point and each chair in 25 contact with a plurality of other chairs to form a chair assembly and an inverted table having legs, one leg interfitted with each of said chairs at outer borders of the latter whereby to unify 30 and secure said assembly.
17. Convertible furniture comprising four 35 chairs, adapted to nest together with their outer borders defining a plane figure of predetermined shape, a table having a top bordered by an encompassing flange which depends during the normal table-functionating position and which flange telescopically encloses said nested chairs when said table is in an inverted position, the back rests of some of said chairs being in lateral edge abutment while supported upon the inverted table, other borders of a pair of chairs being in abutment. 80
18. Convertible furniture comprising four chairs and a table having legs and top bordered by an encompassing flange which depends during the normal table-functioning position and which flange encloses the lowest leg portions of said chairs when resting upon the flange enclosed area of the inverted table, said table legs and chairs being adapted for interfitted connection. 85
19. Convertible furniture comprising a plurality of chairs having edges adapted contactually to nest together and each provided with a hole, a table provided with a plurality of legs and having its top bordered by a flange projecting in the same direction as said legs, said flange conforming to outer borders of said chairs when nested together and when in its inverted position snugly enclosing the bases of said chairs, said table legs each adapted to occupy a hole in a different one of the chairs whereby a modified, composite and interlocked chair assembly is achieved. 90
20. Convertible furniture comprising a table including hinged legs and a top, four chairs 95 adapted to have their seats in interfitted abutting relation and then to rest upon equal segments of said table top while the table is inverted, the backs of certain of said chairs being fashioned with slots for occupancy by folded legs respectively whereby to interlock the chairs and table as an assembly to produce a different article of furniture. 105
